SAFETY PIN OR THE LIKE

Eugene S. Drake, 2836 Kansas Ave., South Gate, Calif.

Filed Feb. 18, 1965, Ser. No. 83,864

Term of patent 14 years

(Cl. D86—10)

Portions of FIGURES 5 and 6 have been shown broken away for illustrative purposes only.

I claim:

The design for a safety pin or the like, substantially as shown and described.
